UNITED STATES PATENT OFFICE.

EDWARD M. NEWCOMB, OF MINNEAPOLIS, MINNESOTA.

WINDOW-SCREEN.

1,200,010.

Specification of Letters Patent.

Patented Oct. 3, 1916.

Application filed September 2, 1915. Serial No. 48,700.

To all whom it may concern:

Be it known that I, EDWARD M. NEWCOMB, a citizen of the United States, residing at Minneapolis, in the county of Hennepin, State of Minnesota, have invented certain new and useful Improvements in Window-Screens; and I do hereby declare the following to be a full, clear, and exact description of the invention, such as will enable others skilled in the art to which it pertains to make and use the same.

This invention relates to new and useful improvements in screens particularly of that type adapted to be positioned outwardly of the sash and to engage the usual blind stop rails whereby they may be held in place.

It is the object of the present invention to provide such a screen structure which is provided with means to adapt it to fit between windows of various sizes within certain limits in such manner as to provide against the occurrence of any opening through which flies or any other insect may gain access to enter the house.

It is further the object of the present invention to provide such a screen structure which may be readily attached to or detached from a window and which is of relatively simple and exceedingly strong structure, it being specifically an object in this latter connection to provide means whereby the adjusting feature of the screen to adapt it to windows of various sizes serves as an efficient brace means for the screen structure to promote proper rigidity and strength.

With the above and other objects and advantages in view, the invention resides more particularly in the novel combination, formation and arrangement of parts as more fully described hereinafter and pointed out in the appended claims.

Reference is had to the accompanying drawings, wherein similar characters of reference designate corresponding parts throughout the several views, and in which:

Figure 1 is a side elevation of a window with the improved screen attached thereto. Fig. 2 is a transverse sectional view through the window with the screen in place therein. Fig. 3 is a perspective view of one corner portion of the screen having the improved width adjusting means associated therewith. Fig. 4 is a plan view of the blank from which the corner members are formed. Fig. 5 is a detail sectional view on line 5—5 of Fig. 3.

Referring now more particularly to the accompanying drawings, the screen is shown as comprising a rectangular frame formed of the strips 5 and secured to each of the strips 5 are the longitudinally extending strips 6 which are of substantially the widths of the blind rib or strip of a window and these strips 6 coact with the strips 5 to form members substantially T-shaped in cross section. These strips are secured to the strips 5 by suitable nails or other securing means 7, and clamped between said strips and the strips 5 are the edges of a foraminous fabric body 8.

Applying this screen, the width of the frame is greater than the width between the blind stops which are designated at 9, so that the outer edges of the side strips 5 will abut against said stops and the strips 6 are extended inwardly of and spaced from said stops. The screen is secured in this position by suitable screws or other means 10 passed through the strips 6 and engaged in the blind stops. Thus the strips 6 serve as the attaching means for the entire screen to a window, they serve as the attaching means of the screen fabric of the body of the screen and they further serve to brace the strips 5, which can therefore be made of relatively light material.

The attachment of the screen as described does not interfere with the raising and lowering of the windows, and the top strip 6 lies substantially in the plane of the bottom sill of the top window sash so that ingress of flies between the top of the screen and the window is prevented.

To prevent flies from passing through the space between the strips 6 and the blind stops 9 and at the time to provide an efficient corner brace for the screen, triangular plates 11 are provided for the corners of the screen and are disposed between the respective strips 5 and 6, being secured by the securing means 7 which hold the strips together, these strips being of such size that their shorter sides coincide with the outer faces of the strips 6 and their longer sides lie inwardly of the juncture of the inner edges of the strips 5. The vertical side of each plate 11 has its upper portion extended at 12 and bent to lie over the outer face of the adjacent strip 6, and this portion 12 is bent upwardly of said strip, and then over the top of the strip 6 and slidably secured as by the pin 13 passed through a longi-

tudinal slot 14 therein. The portion 12 is split from the top corner of the plate a considerable distance downwardly and has a resilient outward tendency to urge it 5 against the blind stop. A suitable securing means 15 is used to attach the lower end of the member 12 which thus forms substantially a filler strip to the strip 6.

The plates 11 efficiently brace the corners 10 of the screen and the resilient filler strips efficiently close the space between the screen and the blind stop to prevent ingress of flies. As the plates 11 and the filler member are made all in one sheet of metal, facility to 15 manufacture as well as simplicity of structure is promoted. The lower corners of the screen may be braced by plates 16 similar to the plates 12 but without the filler strip extensions.

20 While I have illustrated and described a particular embodiment of my invention, I have merely done so for the sake of convenience and I do not wish to be limited to that particular embodiment as it is obvious 25 that numerous changes may be made within the details of construction thereof without in any way departing from the spirit of the invention or exceeding the scope of the appended claim.

What I claim is:—

30 A screen of the class described comprising a rectangular frame formed of strips adapted to abut against the outer portions of the blind stops of a window, longitudinal strips secured on the faces of the frame strips and substantially the width of a blind stop, means for securing said strips to the blind stops of a window, and a body fabric 35 having its edges disposed between and held by the securing means of the first mentioned strips to the body strips, a reinforcing plate 40 at the upper corners of the screen disposed between and secured by the securing means of the first named strips, an extension from 45 said plate of substantially the width of the second named strips disposed along said strips, the upper end of said extension being bent over and slidably secured to the top of the second strip and said extension having a resilient outward tendency to form an adjustable filler between the respective second named strips and the blind stop.

45 In testimony whereof, I affix my signature, in the presence of two witnesses.

50 EDWARD M. NEWCOMB.
